Primary Examiner — Cynthia Ramirez*Assistant Examiner* — Darcy Fabre(74) Attorney, Agent, or Firm — Fross, Zelnick, Lehrman & Zissu, P.C.; Charles T. J. Weigell, Esq.(57) CLAIM

The ornamental design for a perfume case as shown and described.

DESCRIPTION

FIG. 1 is a front perspective view of a perfume case showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the perfume case in FIG. 1, shown in an open position;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines in the drawings show portions of the perfume case which form no part of the claimed design.
